United States Patent Office.

BENAIAH FITTS, OF NEWARK, NEW JERSEY, ASSIGNOR TO THE GOULD MACHINE COMPANY, OF THE SAME PLACE.

Design No. 2,672, dated June 11, 1867.

DESIGN FOR A STEAM FIRE ENGINE.

The Schedule referred to in these Letters Patent and making part of the same.

TO ALL WHOM IT MAY CONCERN:

Be it known that I, BENAIAH FITTS, of Newark, county of Essex, State of New Jersey, have originated or produced a new Design for Steam Fire Engines, of which the following is a full, clear, and exact description, reference being had to the accompanying photographs making a part of this specification.

Figure 1 is a side view.

Figure 2 is a view taken nearly in front.

a is the boiler, *b b* are crane necks, fastened to the boiler at one end, and are connected with the forward axles at the other end by means of being fastened to a cylindrical stand, *c*, in which is a rubber spring, and through which a king-bolt passes. *d* is a water-tank, to carry water to supply the boiler, and when the engine is made to be drawn by horses, it is used for a seat for the driver. *e e e e* are scroll-shaped brackets, used for carrying the hose pipes and suction hose. *ff*, fig. 2, are the suction hose. They lie on the top of brackets *e e e e*, and held in place by spring clasp; *g g* are hose pipes; *h* is the air-chamber, mounted with a lamp, with lamps at each side; *i* is the steam cylinder; *m* are the pumps; *n* the balance-wheel; the whole being mounted upon wheels, as shown.

The peculiar feature of this design is in the form of the crane neck *b b*, the curves being such as shown, together with the brackets *e e e e*, carrying the hose in connection with the other parts, all of which being so formed and constructed as to combine symmetry, strength, and convenience.

What I claim as my invention, and desire to secure by Letters Patent, is—

The design of steam fire engines as herein set forth and shown.

BENAIAH FITTS.
